UNITED STATES PATENT OFFICE.

PER UTNE, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

WARNING-SIGNAL FOR GRADE INTERSECTIONS OF RAILWAYS AND HIGHWAYS.

1,317,338.

Specification of Letters Patent. Patented Sept. 30, 1919.

Application filed December 15, 1915. Serial No. 66,991.

To all whom it may concern:

Be it known that I, PER UTNE, formerly a subject of the King of Norway, having filed my declaration of intention for naturalization in the United States, residing at 5 Edgewood borough, in the county of Allegheny and State of Pennsylvania, have invented certain new and useful Improvements in Warning-Signals for Grade Intersections of Railways and Highways, of which the following is a specification.

My invention relates to warning signals for grade intersections of railways and highways; more particularly it relates to signals 15 of this type comprising a pendulum which is adapted to swing when a train is approaching the highway.

I will describe one form of signal embodying my invention and then point out 20 the novel features thereof in claims.

In the accompanying drawings, Figure 1 is a perspective view of one form of signal embodying my invention located adjacent a grade intersection of a railway and a highway. Fig. 2 is a vertical sectional view on the line II-II of Fig. 3 showing the operating mechanism of the signal shown in Fig. 1. Fig. 3 is a sectional view on line III-III of Fig. 2 looking in the direction 25 of the arrows. Fig. 4 is a view showing in detail part of the mechanism for controlling the angular position of shaft 90. Fig. 5 is a view showing the position of part a of shaft 90 when the pendulum is at the 30 left hand end of its stroke. Fig. 6 is a view showing the position of part a of shaft 90 when the pendulum is at the right hand end of its stroke. Fig. 7 is a view showing latch 92 in engagement with part a of shaft 40 90. Fig. 8 is a diagrammatic view showing one form and arrangement of circuits and circuit controller for the control of the signal.

Similar reference characters refer to similar parts in each of the several views.

In Fig. 1, I have shown a grade crossing of a railroad track T and a highway H. Adjacent the crossing and visible from the highway at a distance from either side of 50 the railroad track is located a vertical pole 1 carrying adjacent its upper end a railroad crossing sign S of the usual type. Immediately below the sign, pole 1 supports by means of brackets 2 a crossing signal em-

bodying my invention. This signal comprises a casing 3 containing mechanism described hereinafter for oscillating a pendulum 4, carrying a disk 6 on both sides of which is printed the word "Stop" or a similar warning legend. Mounted on the pole 1 55 below the crossing signal is a board 5 on which is printed another warning legend such as "Look and listen".

When it is safe to cross the railroad track, i. e., when there is no train approaching the 60 crossing within a given distance from either side thereof, the signal mechanism holds pendulum 4 inclined to the right so that disk 6 occupies the space between two vertical shields 7 and 7^a clamped to pole 1. 65 Shields 7 and 7^a are of such size and so situated as to completely hide disk 6 from view from either side of the track. Upon the approach of a train, the signal mechanism releases the pendulum from its locked position between the two obscuring shields and 70 oscillates the pendulum until the train has passed the crossing. The swinging disk with its warning legend constitutes a very conspicuous and therefore effective warning to 75 traffic. For night indications I provide a red light 8 which is carried by the pendulum 4 and which is controlled as I shall explain hereinafter, so that it is illuminated when the pendulum swings, but is extinguished 80 when the pendulum is locked in its inclined position. The swinging red light, like the swinging lamp of a flagman, constitutes a well known and conspicuous danger signal. I shall now describe the mechanism by which 85 the pendulum is oscillated.

With reference to Figs. 2 and 3, 11 designates the back wall of the mechanism casing 3 which has been partly broken away. Fixed to the wall 11 by means of bolts 13 is a 90 bracket 12. Suspended from this bracket are three electromagnets, 14, 15 and 16, these magnets being attached to the bracket by means of their cores, which extend through holes in the horizontal portion of the bracket 100 and are secured in place by nuts 17 screwed over the threaded ends of the cores. Each electromagnet comprises two coils which in Fig. 2 are located one directly behind the other, so that only one coil of each magnet 105 appears in this view. Fig. 3 shows both coils a and b of electromagnet 14. Magnets 14 and 15 are for the purpose of oscillating

the pendulum by means of their armatures 37 and 38, as described hereinafter. Magnet 16 is for the purpose of latching the pendulum in its extreme right hand position as 5 hereinafter described.

Reference characters 21 and 22 designate two plates of sheet metal of which only plate 22 appears in Fig. 2. These plates are rigidly held a distance apart by means of four 10 stay bolts 23, 24, 25, 26. Each stay bolt comprises a tube *c* whose outer surface is threaded adjacent the ends of the tube to receive nuts *d*. Then the ends of the tubes are inserted through corresponding holes in plates 15 21 and 22 respectively, so that the faces of the plates bear against nuts *d*. Finally nuts *e* are screwed over the outer ends of tubes *c*, so that they bear against the outer faces of the plates, which are thus rigidly fixed between 20 two nuts on each stay bolt. This framework is mounted on the back wall 11 of the mechanism casing by means of bolts 29 the shanks of which extend through holes in wall 11 and tubes *c* of the stay bolts above 25 described. Nuts 28 are screwed over the threaded ends of the bolts which protrude beyond the outer ends of the tubes *c*, so that when these nuts are tightened they clamp the tubes rigidly against the back wall. 30 Thus the framework is firmly fixed with respect to the electromagnets.

A horizontal shaft 31 is mounted adjacent the upper end of the framework in ball bearings 32 and 33. Each ball bearing is 35 secured in a receptacle 34 having a tubular extension which passes through a hole in one of the plates 21 and 22 and is spun over the edge of the hole as shown on the drawing, so that the receptacle is firmly fixed in 40 the plate. Fixed to the shaft 31 by means of a pin 36 is a casting 35 to which the armatures 37 and 38 are secured by means of screws 39. As apparent from Fig. 2, armature 37 swings into engagement with the 45 poles of magnet 14 when casting 35 swings in a clockwise direction and armature 38 swings into engagement with the poles of magnet 15 when the casting swings in the reverse direction. It follows that by alternate energization of magnets 14 and 15, casting 50 35 can be made to oscillate.

A hollow shaft 46 is mounted in ball bearings 47 and 48 which are mounted in plates 21 and 22 in the same manner as are bearings 32 and 33. Two circular plates 51 and 52 are mounted on shaft 46 and rigidly secured parallel to each other by means of stay-bolts designated 54 to 60. Mounted on the bolt 60 is a ball bearing 44 which is held 60 in place at the middle of this bolt by two sleeves 62 and 63. Depending from the casting 35 are two strips of spring steel which are attached to the casting by a rivet 43. Springs 41 and 42 are bent at their lower extremities to clamp between them the outer

race of ball bearing 44. From this construction it is apparent that when casting 35 is caused to oscillate on its shaft by means of the electromagnets, disks 51 and 52 are oscillated through the medium of springs 41 and 42. 70

The pendulum arm 4 is suspended from shaft 46 by means of a hook-shaped strip 71, preferably of spring steel, which is capable of absorbing shock when the pendulum is suddenly stopped. The hook end of this strip 71 is clamped to the shaft 46 by means of a bolt 72. The pendulum arm 4 is attached to the lower end of strip 71 by means of clamps 73 and 74. The arm 4 is 80 hollow so that wires 124 and 125 may be led therethrough to the lamp 8—(Fig. 1). Bolts 55 and 56 are so located that their shanks engage respectively the two sides of strip 71 so that the pendulum is caused to swing 85 when the disks are oscillated.

The operation of the mechanism as thus far described is as follows: Assume that the pendulum is held in its extreme right hand position so that the signal indicates safety. 90 At the approach of a train the pendulum is automatically released (as I shall describe hereinafter) so that it swings to the left. During this swing of the pendulum electromagnet 15 is energized through the medium 95 of a circuit controller which I shall describe hereinafter. The magnetic attraction of armature 39 is transmitted to the pendulum by means of spring 41 which presses on ball bearing 44. Similarly, when the pendulum swings in the reverse direction, magnet 14 is energized so that spring 42 presses on bearing 44 and drives the pendulum from left to right. It may be noted here that at the end of each stroke the pendulum is gradually brought to rest by means of one of the springs 41 or 42. Thus, when the pendulum is swinging from left to right casting 35 turns clockwise until it is suddenly arrested by the engagement of armature 37 with the poles of magnet 14. The pendulum has at this time considerable momentum and therefore continues to swing to the right so that ball bearing 44 presses against spring 41 and deflects it outwardly until the pendulum is gradually arrested. The spring pressure then causes a rapid acceleration of the pendulum in the reverse direction. Spring 42 acts similarly at the left end of the stroke of the pendulum. 110

For holding the pendulum in an inclined position when the signal indicates safety, I provide a latching mechanism which I will now describe. Two arms 81 and 82 are freely mounted on shaft 31 and carry at 125 their ends an armature 83 adapted to engage the pole faces of magnet 16. A finger 95 of resilient material is secured to the under side of casting 35 and extends downward between arms 81 and 82 so that it engages the side of 130

a pin 84 connecting the two arms. A pair of links 85 and 86 are pivotally connected to arms 81 and 82 by the pin 84. The opposite ends of these links are connected by a pin 5 87 to cranks 88 and 89 (see Fig. 4) which are pin-connected to a shaft 90 mounted in ball bearings in plates 21 and 22. A portion of shaft 90 is cut away to form a corner α at the middle of the shaft, as shown in Figs. 10 2 and 4. A latch 92, the end of which is toothed as shown for engaging this part of shaft 90, is mounted on bolt 57 between plates 51 and 52. The latch 92 is biased to normally rest against bolt 58 by a spring 15 93 which is attached to the latch by screws 94 and the free end of which spring bears against bolt 59.

When the pendulum is swinging and magnet 16 is not energized, the latching mechanism operates as follows. When the pendulum arrives at its middle position, swinging, say, from right to left, the various members of the apparatus are in the positions indicated in Fig. 2. As the pendulum continues its movement, finger 95 bearing against bolt 84 causes armature 83 to swing toward the poles of magnet 16. This causes links 85 and 86 to turn shaft 90 clockwise so that at the left hand end of the stroke of 20 the pendulum, the portion α of shaft 90 is in the position shown in Fig. 5. During this latter movement of the pendulum the toothed end of latch 92 is swung to the dotted position marked p in Fig. 2, because 25 disks 51 and 52 between which the latch is mounted are turned clockwise as the pendulum swings to the left. When the pendulum reverses its movement, armature 30 83 recedes from the poles of magnet 16 due to its weight. This causes links 35 85 and 86 to turn shaft 90 counter-clockwise through the position shown in Fig. 2 into the position shown in Fig. 6 which latter position it occupies when the 40 pendulum reaches its extreme right hand position. In the meantime the toothed end of latch 92 is carried counter-clockwise past the position shown in Fig. 2 to the position shown in Fig. 6. It will be noted that the 45 toothed end of the latch swings just clear of shaft 90. Similarly, the latch clears this shaft when the pendulum again reverses and swings from right to left. In this manner the pendulum continues to swing indefinitely as long as the requisite amount of 50 energy is supplied by the electromagnets.

However, when magnet 16 is energized, the pendulum is latched in its extreme right position so that its disk 6 disappears between 55 shields 7 and 7 α , and remains there until the latching magnet is deenergized. For, when armature 83 is brought up to the poles of magnet 16 as the pendulum swings to the left, the magnet grips the armature and 60 holds it there when the pendulum reverses

its stroke. In other words, when the latch 92 swings counter-clockwise, shaft 90 remains in the position in which it is shown in Fig. 5. Latch 92 does not swing clear of shaft 90, as before, because the corner α 70 of the shaft now protrudes into the path described by the teeth of the latch. Nevertheless, the pendulum is able to complete its stroke to the right because spring 93 yields slightly as each tooth of the latch is 75 drawn over the projecting corner α . When the pendulum comes to a standstill and begins to reverse by force of gravity, one of the teeth of the latch engages the corner of shaft 90 as shown in Fig. 7, thereby preventing the return movement of the pendulum. Although it may require considerable force to stop and hold the pendulum in the inclined position, still, only a small part 80 of this force is transmitted to the armature 83 of the holding magnet 16, because the force exerted by latch 92 on shaft 90 acts at so small a distance from the center of the shaft that it can create but a comparatively small torque tending to rotate the shaft. 90

When magnet 16 is deenergized, the pendulum is immediately released and is free to swing as described hereinbefore. For, both the weight of armature 83 and the torque on shaft 90 cause this armature to 95 drop away from the magnet poles, so that shaft 90 is immediately turned into the position shown in Fig. 6. The latch is now free to swing past shaft 90 and the pendulum oscillates in the manner hereinbefore described until it is again latched by the re- 100 energization of magnet 16.

One important feature of my invention is that each time the pendulum swings to the left it raises the latching armature 83 into a 105 position close to the poles of latching magnet 16, so that when the pendulum is to be latched the magnet 16 is required to exert only enough energy to hold its armature in the latching position; this magnet is not required to draw its armature into the latching position through a large air gap and therefore may be designed to consume but little electrical energy. 110

Any suitable means may be used to control the electromagnets. In Fig. 8 I have shown one form and arrangement of apparatus suitable for this purpose. Reference character K designates a friction clutch comprising two members 100 and 101 of 115 insulating material. The upper ends of these members serve as jaws to clamp between them a contact finger 102, a bolt 103 being used to bind the members together. The clutch is mounted on the same shaft 46 120 which supports the pendulum. The lower ends of members 100 and 101 are clamped together by means of a bolt 104 bearing on a spring 105. By adjustment of the spring 125 pressure, the friction between clutch K and 130

shaft 46 can be regulated to the desired value. Contact finger 102 co-operates with stationary contact points 106 and 107. When the pendulum is latched up in the inclined 5 position, finger 102 engages contact point 106. When the pendulum is released and swings to the left, finger 102 immediately breaks contact with point 106 and swings at once into engagement with point 107. 10 Further movement of the contact finger is prevented by the contact point and therefore clutch K slips as the shaft continues to turn until the pendulum arrives at the left end of its stroke. As soon as the pendulum 15 reverses, finger 102 leaves point 107 and makes contact with point 106 so that the clutch slips in the reverse direction until the pendulum again reverses. This operation is repeated for every period of the 20 pendulum.

For controlling the length of time during which magnets 14 and 15 are energized in each period of the pendulum, I provide a contact segment 130 mounted on a ring of 25 insulating material 131 fixed to shaft 46. Stationary contact fingers 130^a and 130^b co-operate with segment 130, which is of such length that one contact finger or the other breaks contact with segment 130 before the 30 pendulum arrives at one extreme position or the other.

The circuits for the control of the electromagnets comprise contacts of a relay 109 which is controlled by the presence or absence 35 of a train within a certain distance from the highway crossing, in a manner which is well known to those versed in the art and therefore not described here. Suffice it to state that, when no train is approaching the crossing within a certain distance from either side thereof, relay 109 is energized so that its contact 110 is closed. Magnet 16 is controlled by this contact, the 40 complete circuit being: from battery B, through the wire 111, contact 110 of relay 109, wire 112, magnet 16 and wire 113 to battery B. It follows that as long as contact 110 is closed, magnet 16 is energized. As pointed out hereinbefore, this causes the 45 arrest of the pendulum in the inclined position (indicated by dotted lines in Fig. 8) wherein its disk is concealed between shields 7 and 7^a. The signal is therefore in its safety position.

50 When a train enters the danger zone, relay 109 is de-energized and opens contact 110, but closes contacts 108 and 114. Contact 110 opens the circuit of magnet 16, so that this magnet releases the pendulum and 55 allows it to swing freely. After the pendulum has swung through several degrees, it closes contacts 130 and 102—107 and causes the energization of magnet 15 through the following circuit: from battery B, through 60 wire 120, contact 130, wire 133, contact

102—107, magnet 15, wires 121 and 122, contact 108, wire 123 to battery B. Magnet 15 drives the pendulum from right to left, but before the pendulum reaches the end of its stroke segment 130 breaks contact with 70 finger 130^a so that the circuit of magnet 15 is opened, leaving the pendulum free to reverse. Just after the pendulum has begun its swing from left to right, finger 102 breaks contact with point 107 and engages 75 contact point 106 and contact finger 130^a engages segment 130. Magnet 14 is now energized through the circuit: from battery B, through wire 120, contact 130, wire 133, contact 102—106, magnet 14, wire 122, contact 108 and wire 123 to battery B. This magnet drives the pendulum from left to right until it is de-energized just before the pendulum reaches its extreme right position. Thus, the controller automatically energizes 80 first one and then the other magnet so that the pendulum continues to swing as long as relay 109 is de-energized.

Red lamp 8 is illuminated while a train is in the danger zone, that is, while relay 109 90 is de-energized, by current in the following circuit: from battery B, through wire 111, contact 114 of relay 109, lamp 8, and wire 124 to battery B.

When the train passes the crossing, relay 95 109 is re-energized and breaks the circuit for magnets 14 and 15 at contact 108 and opens the circuit for light 8 at contact 114. The relay also closes the circuit for magnet 16 at contact 110 so that the pendulum is 100 arrested in the safety position where it remains until the relay is again de-energized by the approach of another train.

Although I have herein shown and described only one form of apparatus embodying my invention, it is understood that various changes and modifications may be made therein within the scope of the appended claims without departing from the spirit and scope of my invention. 105

Having thus described my invention what I claim is:

1. A signal comprising a pendulum, means for causing said pendulum to swing to and fro to give one indication, electro-magnetic means comprising an electromagnet member and an armature member one of which is fixed and the other of which is movable and is biased away from the fixed member, means operatively connected with 115 the pendulum for shifting the movable member toward the fixed member, the movable member being then held to the fixed member if the electromagnet is energized, and means controlled by the movable member when held in such shifted position for retaining the pendulum in an inclined position to give another indication. 120

2. A signal comprising a pendulum, means for causing said pendulum to swing 125 130

to and fro to give one indication, electromagnetic means comprising an electromagnet member and an armature member one of which is fixed and the other of which is 5 movable and is biased away from the fixed member, means operatively connected with the pendulum for shifting the movable member toward the fixed member, the movable member being then held to the fixed 10 member if the electromagnet is energized, and means comprising an element operatively connected with said movable member and an element operatively connected with the pendulum, which elements cooperate to 15 retain the pendulum in an inclined position to give a different indication when the movable member is held in such shifted position.

3. A signal comprising a pendulum, 20 means causing said pendulum to swing to and fro to give one indication, electromagnetic means comprising a fixed member and a member movable toward and away from said fixed member and biased away therefrom, means operatively connected with the pendulum for shifting said movable member toward the fixed member, said movable member being then held to the fixed member, if the electromagnetic means is energized, and means controlled by said movable member when held to the fixed member for retaining the pendulum in an inclined 25 position to give a different indication.

4. A highway crossing signal comprising 30 a pendulum, means for causing said pendulum to swing to and fro continuously to give one indication, retaining means for holding said pendulum in an inclined position to give a different indication, an electromagnet 35 and armature for controlling said retaining means, and means operatively connected with said pendulum for moving said armature toward the poles of said electromagnet each time that the pendulum swings toward 40 the position opposite to that in which it is held by said retaining means.

5. A highway crossing signal comprising 45 a pendulum, means for causing oscillation thereof, means for retaining the pendulum in an inclined position, means operatively connected with the pendulum for moving said retaining means into operative position, and electromagnetic means adapted when energized to hold said retaining means 50 in operative position.

6. A highway crossing signal comprising 55 a pendulum, means for causing oscillation thereof, means for retaining said pendulum in an inclined position at or near one end of its stroke, said retaining means being moved 60 into retaining position during each swing of the pendulum toward the other end of its stroke, and electromagnetic means for holding said retaining means in retaining position.

7. A highway crossing signal comprising a base, a pendulum suspended therefrom, a locking-mechanism comprising a member on said pendulum and another member on said base, means operatively connected with 70 the pendulum for moving said locking-mechanism into locking position, and an electromagnet adapted to retain said locking mechanism in locking position.

8. A highway crossing signal comprising 75 a base, a pendulum suspended therefrom, and means for locking the pendulum in an inclined position, said means comprising an electromagnet having a pivotally mounted armature, a member on said pendulum and 80 a member pivotally mounted on said base, means for oscillating said pivotally mounted locking member and said armature when said pendulum oscillates, whereby said pivotally mounted member is brought into locking 85 position and said armature is moved into engagement with its magnet poles once every period of the pendulum.

9. A highway crossing signal comprising 90 a base, a pendulum suspended therefrom, a member operatively connected with the pendulum, a locking member on the base adapted when in locking position to engage said first-mentioned member to hold the pendulum in an inclined position, means operatively connected with the pendulum for moving said locking member into locking 95 position, and an electromagnet adapted when energized to hold said locking member in locking position.

10. A highway crossing signal comprising 100 a pendulum, a locking device for retaining said pendulum in an inclined position, an electromagnet, means for controlling said locking device by the magnetic circuit of said electromagnet, and means operatively connected with the pendulum for periodically closing the magnetic circuit of said electromagnet.

11. A highway crossing signal comprising 110 a base, a pendulum suspended therefrom, a locking device for retaining said pendulum in an inclined position, an electromagnet having an armature pivotally mounted on said base, means for controlling said locking device by said armature, and means operatively connected with the pendulum for swinging said armature into engagement with the magnet poles during 115 every period of the pendulum.

12. A highway crossing signal comprising 120 a base, a pendulum suspended therefrom, means for oscillating the pendulum, a member operatively connected with the pendulum, a locking member on the base adapted when in locking position to engage said first-mentioned member to hold the pendulum in an inclined position, means controlled by the said oscillating means for periodically swinging said locking member 125 130.

into locking position, and an electromagnet adapted when energized to hold said locking member in locking position.

13. A highway crossing signal comprising
 5 a base, a pendulum suspended therefrom, means for oscillating the pendulum, an electromagnet having an armature pivotally mounted on said base, a locking device controlled by said armature for retaining said
 10 pendulum in an inclined position, and means operatively connected with said pendulum for swinging said armature into engagement with the magnet poles once during every period of the pendulum.
14. A signal comprising a pendulum, means for causing said pendulum to swing to and fro, a locking member movable into and out of a position wherein it operates to retain the pendulum in an inclined position
 20 at or near one end of the stroke of the pendulum, means operatively connected with the pendulum for moving said locking member into operative position while the pendulum is swinging toward the opposite end
 25 of its stroke, and electromagnetic means for holding said locking member in its operative position.
15. A signal comprising a pendulum, means for causing said pendulum to swing to and
 30 fro, a locking member operatively connected with the pendulum, a second locking member movable into and out of a position wherein it co-operates with the first member to retain the pendulum in an inclined position
 35 at or near one end of the stroke of the pendulum, means operatively connected with the pendulum for moving said second member into operative position while the pendulum is swinging toward the opposite end of
 40 its stroke, one of said locking members being resilient to permit the full return movement of the pendulum to the position wherein it is locked, and electromagnetic means for holding said second locking means in
 45 operative position.

16. A highway crossing signal comprising a pendulum, means for causing oscillation thereof, means for retaining said pendulum in an inclined position, electromagnetic means for holding said retaining
 50 means in operative position and comprising a magnet member and an armature member, and means operatively connected with said pendulum for moving said retaining means into operative position and for
 55 moving one member of said electromagnetic means toward the other.

17. A signal comprising a pendulum, means for causing said pendulum to oscillate to give one indication, a member operatively connected with said pendulum for movement into a latching position, electromagnetic means for retaining said member in latching position, and a second member
 60 operatively connected with the pendulum and arranged to coact with the first member to latch the pendulum in an inclined position to give a different indication when the first member is retained in latching position.

18. A signal comprising a pendulum, means for causing said pendulum to oscillate, a member operatively connected with said pendulum and moved into latching position each time the pendulum swings toward one
 75 end of its stroke, electromagnetic means for retaining said member in latching position, and a second member operatively connected with the pendulum and arranged to coact with the first member to latch the pendulum
 80 at the opposite end of its stroke when the first member is retained in latching position.

In testimony whereof I affix my signature in presence of two witnesses.
